ILLUMINATING DEVICE

John W. Martin and Robert W. Martin,
Brooklyn, N. Y.

Application August 9, 1939, Serial No. 289,198

4 Claims. (Cl. 240—6.4)

This invention relates to illuminating devices.

One object of the invention is to provide a device of the character described having improved means providing a combination portable light 5 and accessory holding device.

Another object of the invention is the provision of an improved combination portable lighting device of the searchlight type and a first aid kit in a simple compact case structure.

10 We have perceived the important utility of providing an easily accessible first aid kit for an operator working on machinery, as for instance, on the mechanism of an automobile. The operator may scratch or cut himself, especially if he 15 is an amateur, and may require a solvent to clean the wound, and an antiseptic together with bandage or adhesive plaster material, as the case may be. During the night it is inconvenient to search for such articles whereas with the present invention, they are instantly at hand.

In fact, it is extremely rare for an automobilist to carry first aid of the type mentioned in his car. Therefore the present invention will solve a substantial need, which need no longer be affected by 25 the shortsightedness or negligence of the operator. Thus infections may be avoided, and the work of adjustment or repair expedited, with a consequent decrease in the likelihood of the occurrence of accidents in driving. Even during the 30 day, when a searchlight may or may not be required, this combination utility may serve the same valuable functions.

It will be perceived that by the term "article" as herein used is meant any article which it may 35 be feasible to associate with the searchlight. For example, a simple telegraphic device may be employed in place of the medical kit, or in addition to the latter, and supplied with current from the lamp battery, and exposed for operation on opening the main casing as in the improved manner hereinafter described.

It is therefore an object of the invention to overcome the difficulties and to secure the advantages above mentioned by a device which is simple, light in weight, compact, easy and convenient to operate, durable, reliable, inexpensive, and highly efficient in use.

Other objects and advantages of the invention will become apparent as the specification proceeds.

With the aforesaid objects in view, the invention consists in the novel combinations and arrangements of parts hereinafter described in their preferred embodiments, pointed out in the 55 subjoined claims, and illustrated in the annexed

drawings, wherein like parts are designated by the same reference characters throughout the several views.

In the drawings:

Fig. 1 is a view in front elevation showing a device embodying the invention; in closed position.

Fig. 2 is a view in side elevation thereof.

Fig. 3 is a top plan view of a part thereof and a horizontal sectional view of another part of the device, in open position.

Fig. 4 is a view in front elevation of the device in open position.

Fig. 5 is a sectional view taken on the line 5—5 of Fig. 4.

Fig. 6 is a fragmentary schematic front view in open position of the device with parts removed.

Fig. 7 is a fragmentary schematic front view in open position showing a modified device.

Fig. 8 is a view in elevation of another modification of the invention.

Fig. 9 is a view in section with parts in elevation of a removed section thereof.

Fig. 10 is a top plan view of said removed section.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawings, therefore, are submitted merely as showing the preferred 35 exemplification of the invention.

Referring in detail to the drawings, 15 denotes a device embodying the invention. The same may comprise a unitary housing or casing, including a first case member 16 and a second 40 case member 17, movably related, as by being hingedly interconnected at 18, and releasably interlocked as by any releasable spring finger or catch 19. The member 16 may be the main case, and the member 17 may be the cover therefor. Any wire handle 20 may be pivotally connected to the case 16, and an auxiliary catch 21 may be connected to the case 16 for a different type of mounting for the device 15.

In the upper part of the case 16 there may 50 be provided a light generating means 22, which may include a lamp 23 or other light source, and batteries 24, in a suitable circuit controlled by any switch 25. In Fig. 6 is a schematic showing, with top and base spring contacts 26, 27 for the 55

batteries 24, whereby the latter are mounted and connected in circuit. In general, the arrangement is conventional, so that no further detailed showing or explanation is required, it being understood that the contacts 26, 27 are suitably insulatingly mounted on the case 16, and the batteries covered by any easily removable plate or open box-like element 28 wedged or snugly fitted in the case 16 and having a hole 29 through which the lamp 23 may project. It will be noted that the term light generating means as used herein may pertain to the lamp 23 per se.

Mounted on the member 17 is any light directing or light gathering unit 30 of the lens or reflector type, which may comprise a shell 31 affixed to the member 17 in an opening thereof, and a rim 32 screwed onto the shell for marginally securing between itself and the edge of the shell, a reflector 33 and a glass cover disc 34. The unit 30 thus lies externally at the front of the case member 17, and the reflector has a rear central opening 35 for freely receiving the lamp 23. The details of construction of the unit 30, except as otherwise herein indicated, may be conventional.

When the case members 16, 17 are in closed relationship as in Fig. 2, the lamp 23 is in operative relation to the reflector 33. When the members are moved apart to open position as in Fig. 3, the lamp 23 is withdrawn from the reflector.

One or both of the case members may have article receiving compartments, as indicated at 36 and 37 for the respective case members 17 and 16. These compartments are in register with each other and hence are adapted to form a large chamber, below the light generating unit, which projects from the case member 16 so as to be partially housed by the case member 17 as shown. If desired, the compartment 37 may be divided by a horizontal shelf 38 and may be flanged along its sides and bottom as at 39. The compartment 36 may have dividing or supporting elements such as a plurality of horizontal rods 40 back of which may be placed notes, instructions or other articles.

The compartment 37 is ideally adapted to receive small bottles of iodine, mercurochrome, spirits of ammonia, and small packages of bandage, adhesive plaster, and the like. Bandages prepared in strip form may be placed in the compartment 36 back of the rods 40.

In operation, upon opening the case to the position shown in Fig. 4, the first aid is instantly accessible, and, in fact, may be illuminated by the lamp 23. Then the case may be snapped shut and the device 15 is again available for use in the usual manner. In fact, the device may be used as a flare signal, by substituting a red colored lamp for the white lamp 23.

It is thus seen that a simple and inexpensive case structure is operative for access to lamp, batteries, and to the article or articles retained in the case, such as the first aid kit, and serves to enclose the same, and to bring the lamp into operative relation to its reflector.

In addition to or in lieu of the first aid kit, a modified device 41 may have an article such as a telegraphic unit 42 schematically shown. It will, however, be understood that the unit 42 may be connected to the batteries 24, and that the light 23 may illuminate the same in the open position of the device shown in Fig. 7. To conserve the life of the batteries, the circuit may be so arranged that when the unit 42 is in operation,

the lamp 23 can not be energized. The unit 42 may be disposed in the case member 16a, and may be protectively enclosed when the members 16a and 17a are closed. In all other respects the device 41 may be like the device 15.

In Figs. 8 to 10 is shown another modification of the invention comprising a tubular type of searchlight 43 having a tube 44. At one end thereof is a screw cap structure 45 which may comprise a reflector 46 for a lamp 47. In the upper part of the tube 44 is a compartment 48 for batteries 49, the circuit of which with the lamp 47 is completed through a screw cap 50 for the lower open end of the tube 44, and a coil spring 51 carried by the cap 50 and contacting the base of the lowermost battery 49 and causing reliable contact as required by spring tension of the element 51. Any switch 52 may control the circuit. As thus far described, the device 43 may be conventional.

Below the battery compartment 48 is an article receiving means or chamber 53 in the tube 44 and closed by the cap 50. Preferably the latter carries a holder 54, which may be a longitudinally open or split tube or a plate longitudinally concaved as shown, and rigidly affixed at its lower end to the cap 50 so as to be normally spaced inward from the wall of the tube 44 to readily clear the same. The spring 51 may be affixed to the upper end of the holder 54 so that the operation of the spring is as before. Various articles may be stacked up in the holder 54, and with the latter and the tube 44 held horizontal, the holder may be inserted into the tube 44 without loss of any article, and the cap 50 screwed onto the tube. The spring 51 may act as an inner end wall for the articles, and if the articles are tightly packed, the spring may resiliently bear on the row or column of articles to hold the same in very snug relation. Thus a first aid kit may be embodied in the device 43 which may thus require a lengthening of the tube 44 or merely the use of fewer batteries to afford the necessary internal space.

We claim:

1. A device including a generally flat vertically elongated rectangular casing comprising a plurality of relatively shallow casing sections hingedly interconnected at one edge along a vertical axis to constitute a unitary structure in the open and closed position of the casing, one of said casing sections being a main section and the other being a cover section, means for mounting a plurality of batteries in side by side relation to each other in the upper portion of the main casing section and for mounting a lamp in operative relation to said batteries at a point between the latter, a removable plate at the upper portion of the said main casing section and covering the front side of said batteries and having an opening for said lamp, said plate projecting from the main casing section into the upper part of the cover section, said lamp projecting beyond said plate and removably extending through an opening in the cover section so that the lamp is removed therefrom on opening the casing, said cover section having a reflector external of the casing for cooperative relation with said lamp, said casing sections having individual compartments in the lower portions thereof, said compartments being closed by closing said casing and being otherwise open and being directly accessible and exposed to said lamp on opening said casing, with said plate constituting an auxiliary reflector adapted to project light toward

the interior of the cover section when the casing is opened.

2. A device including a generally flat vertically elongated rectangular casing comprising a plurality of relatively shallow casing sections hingedly interconnected at one edge along a vertical axis to constitute a unitary structure in the open and closed position of the casing, one of said casing sections being a main section and the other 10 being a cover section, means for mounting a plurality of batteries in side by side relation to each other in the upper portion of the main casing section and for mounting a lamp in operative relation to said batteries at a point between 15 the latter, said lamp projecting beyond the main section and removably through an opening in the cover section and beyond the same, a reflector located externally of the casing and mounted on said cover section so as to lie in cooperative relation with the lamp, said casing sections having compartments in their lower portions, closed by closing the casing, and the latter being opened by moving apart the casing sections to thus directly remove the lamp from said reflector so that the lamp is adapted to illuminate 25 said compartments.

3. A device including a generally rectangular vertically elongated casing split along a vertical

plane to provide a first and a second casing section each having a top and bottom wall, and side and end walls, said casing sections being interconnected along a vertical hinge line so as to be relatively swingable for opening and closing the 5 casing, a lamp and battery unit mounted in the upper portion of the first casing section, a concave reflector for the lamp external of the casing mounted on the second casing section, the battery portion of said unit projecting laterally 10 into the upper part of the second casing section, the lamp portion of said unit projecting beyond the battery portion and removably extending through an opening in the second casing section into operative relation to the reflector, the lower 15 portions of the casing sections below said unit providing individual article receiving compartments with the unit forming a top closure for the said compartments, and said casing sections, on being swung apart, affording direct access to 20 the said unit for replacement thereof and to the articles in the said individual compartments.

4. A device according to claim 2, wherein said compartments comprise individual transverse article holding rods parallel to said plane and constituting reinforcements for the casing sections. 25

JOHN W. MARTIN.
